UNITED STATES PATENT OFFICE.

GEORGE A. LEWIS, OF GREENFIELD, MASSACHUSETTS.

SANDPAPER HOLDER.

Application filed July 18, 1924. Serial No. 726,836.

The present invention appertains to a sand paper holder and has for its prime object to provide a device of this nature on which a piece of sand paper may be placed in order that it may be most conveniently utilized.

Another important object of the invention is to provide a holder of this nature having a very simple and efficient construction, one which is reliable, inexpensive to manufacture, strong, durable, easy to manipulate, and well adapted to the purpose for which it is designed.

With the above and numerous other objects in view as will appear as the description progresses, the invention resides in certain novel features of construction, and in the combination and arrangement of parts as will be hereinafter more fully described and claimed.

20 In the drawing:

Figure 1 is a perspective view of the sand paper holder showing a sheet of paper thereon.

Figure 2 is an end elevation thereof,

25 Figure 3 is a side elevation thereof, and

Figure 4 is a fragmentary view of the sand paper holder showing the parts disassembled.

Referring to the drawing in detail it will be seen that the body of the sand paper holder is substantially U-shaped in end elevation so as to include an intermediate plate 5 and side plates 6 and 7. The free edges of the side plates 6 and 7 are provided with L-shaped flanges 8 including sections 9 which extend inwardly toward each other at right angles to the side plates 6 and 7 and sections 10 which extend parallel to the plates 6 and 7. The flange 8 on side plate 7 is provided with a further extension in the form of a lip 11 which extends toward plate 6 at right angles to plate 7. This body is preferably constructed of spring metal and a retaining bar 12 is associated therewith being 45 constructed preferably so as to be round in

cross section and the diameter thereof is substantially equal to the distance between sections 10 of flanges 8. Thus it will be seen a piece of sand paper may be wrapped about the body having one end terminating 50 on the section 10 of the flange 8 on side plate 7 while the other end thereof either terminates on the other section or extends through the space between lip 11 and said last mentioned section 10. The bar 12 is then pushed 55 in between the ends of the sheet of sand paper disposed thus between sections 10 of flanges 8 and, of course, the body will give sufficiently to allow the insertion of this retaining bar and the resilient nature of the 60 body will hold the bar in place thus preventing accidental removal of the sheet of sand paper from the holder.

It is thought that the construction, advantages, and operation of this device will now 65 be clearly understood without any more detailed description thereof. It is desired, however to point out that changes in the details of construction, materials, arrangement of parts, may be resorted to without departing from the spirit or scope of the invention as hereinafter claimed or sacrificing any of its advantages.

Having thus described my invention, what I claim as new is:

A holder of the class described including a U-shaped resilient body terminating in L-shaped flanges one of which is provided with a lip terminating a distance from the other flange in order that a sheet of sand paper or the like may be disposed about the body and the flanges one end extending between the lip and the other flange and means insertable between the flanges to force the sand paper into tight engagement with the flanges 85 all in the manner and for the purpose specified.

In testimony whereof I affix my signature.

GEORGE A. LEWIS.
